UNITED STATES PATENT OFFICE.

SUMNER A. HOVEY, OF STONEHAM, MASSACHUSETTS.

DESIGN FOR A WICK-TRIMMER.

SPECIFICATION forming part of Design No. 30,566, dated April 18, 1899.

Application filed March 18, 1899. Serial No. 709,694. Term of patent 7 years.

To all whom it may concern:

Be it known that I, SUMNER A. HOVEY, of Stoneham, in the county of Middlesex and State of Massachusetts, have invented and 5 produced a new and original Design for a Wick-Trimmer, of which the following is a full, clear, and exact description.

Reference is to be had to the accompanying drawings, forming a part of this specification, 10 in which similar characters of reference indicate corresponding parts in all the views.

Figure 1 is a plan view of the wick-trimmer, showing my design. Fig. 2 is an inverted plan view of the same, and Fig. 3 is a sectional side elevation of the same on the line 15 3 3 in Fig. 1.

The design in its entirety consists of a body A, from which depends an annular flange B,

and knives C extend from the body beyond the peripheral surface of said flange, said knives 20 being spaced equally apart and arranged in the plane of the body and appearing integral therewith, the knife-edges being tangential to the flange, as plainly shown in Fig. 2, the top of the body being ornamented by a handle 25 shown in the form of a transverse rib D.

The leading feature of my design consists in the handled body, the annular flange, and the knives.

I claim—

The design for a wick-trimmer, herein 30 shown and described.

SUMNER A. HOVEY.
